UNITED STATES PATENT OFFICE.

EDMUND SIMPSON, OF NEW YORK, N. Y., ASSIGNOR OF ONE-HALF TO WILLIAM W. DUNCAN, OF RIDGEWOOD, NEW JERSEY.

SIGNAL DEVICE FOR AUTOMOBILES.

1,215,209.

Specification of Letters Patent. Patented Feb. 6, 1917.

Application filed November 4, 1915. Serial No. 59,678.

To all whom it may concern:

Be it known that I, EDMUND SIMPSON, a subject of the King of Great Britain, and residing at New York, in the county of New York and State of New York, have invented certain new and useful Improvements in Signal Devices for Automobiles, of which the following is a specification, such as will enable those skilled in the art to which it 10 appertains to make and use the same.

This invention relates to signal apparatus or devices for use in connection with automobiles and particularly to devices of this class designed to indicate to a following vehicle that a preceding vehicle is about to stop or slow down for the purpose of making a turn, or with the intention of coming to a complete stop; and by means of which a preceding vehicle may also signal 20 to a following vehicle that said preceding vehicle is increasing its speed; a further object being to provide a signal apparatus or device of the class specified, designed particularly to prevent collisions by one car 25 running into another in crowded cities and similar places where the speed of the cars is limited and must be controlled; a still further object being to provide a signal apparatus or device of the class specified which 30 will indicate the speed of a car; and with these and other objects in view the invention consists in a device or apparatus of the class specified, constructed and operating as hereinafter described and claimed.

The invention is fully disclosed in the following specification, of which the accompanying drawing forms a part, in which the separate parts of my improvement are designated by suitable reference characters in 40 each of the views, and in which:—

Figure 1 is a diagrammatic view partially in dotted and partially in full lines, and indicating the method of mounting my improved signal apparatus or device in connection with a chassis or frame of an automobile;

Fig. 2 a back view of a signal box which I employ;

Fig. 3 a view similar to Fig. 2 but showing the parts in a different position;

Fig. 4 a view similar to Fig. 2 but showing a modification;

Fig. 5 a view similar to Fig. 3 but showing the modification shown in Fig. 4, or 55 showing the parts of the form of construc-

tion shown in Fig. 4 in a different position;

Fig. 6 a sectional front view of the signal box shown in Fig. 2 and on an enlarged scale and with parts of the construction broken away;

Fig. 7 a sectional side view of the signal box as shown in Fig. 6;

Fig. 8 a detail back view of a part of the construction of the signal box as shown in Figs. 4 and 5, and on an enlarged scale;

Fig. 9 a partial section on the line 9—9 of Fig. 6 and on an enlarged scale;

Fig. 10 a detail view of a stop sign which is employed in connection with all of the forms of construction shown;

Fig. 11 a sectional detail of a part of the operative construction as shown in Figs. 6 and 7, and on an enlarged scale; and,

Fig. 12 a sectional view of details of the construction shown in Fig. 7 and on an enlarged scale.

In the accompanying drawing, reference being made to Fig. 1, I have indicated at *a* a part of the rear end of the chassis frame of an automobile and at *b* the rear or drive axle which passes through the usual housing *b*² into which passes the drive shaft *b*³, all this construction being of the usual or well-known form.

In the practice of my invention, as shown in the drawing, I mount in a vertical position, and in connection with the rear end of the chassis frame, a signal box or casing *c* which may be connected with said frame or supported in any desired manner, or which may be built into the body of the vehicle or connected therewith, and I also provide the drive shaft *b*³ with a gear *d* which meshes with a pinion *d*² mounted in a suitable support *d*³ through which also passes a flexible shaft *d*⁴ on which the pinion *d*² is secured, and the flexible shaft *d*⁴ passes back through the rear end portion of the chassis frame to the bottom *c*² of the signal box or casing *c*, as clearly shown in Figs. 1, 6, 7 and 11, and said flexible shaft is connected as shown at *d*⁵ in Fig. 11, with the shaft *e* of a governor *e*². The governor *e*² is provided with a supplemental shaft *e*¹ which enters the shaft *e*, and the shaft *e*¹ is provided with a pin *e*⁴ movable in a vertical slot *e*⁵ in the shaft *e*, and the shaft *e*¹ is provided with a block head *e*⁶ having a threaded and detachable cap *e*⁷ with which is connected a vertically arranged rod *e*⁸, this connection being made

by a universal joint connection as shown at e^6 , the rod e^8 being provided with a ball which is held in connection with the block head e^6 by the cap e^7 .

5 Mounted in the bottom portion of the box or casing c and above the operative parts of the governor e^2 is a horizontal shaft f having permanent end bearings f^2 in which it is secured and which are secured to the sides 10 of the box or casing and on which are wound spiral springs f^3 , one end of which is secured to the said bearings.

15 Mounted on the shaft f between the bearings f^2 is a sleeve f^4 between which and said shaft are roller bearings f^5 which extend the full length of said sleeve f^4 , and said sleeve is provided at its opposite ends with grooved wheels f^6 to which one end of the springs f^3 are secured, and wound on the 20 wheels f^6 are wire cords g , the corresponding ends of which are secured to the wheels f^6 , and the other ends of which are secured to one end of a flexible shutter g^2 , the other end of which is secured to and adapted to 25 be wound on a drum g^3 mounted in the top of the box or casing c and having a central sleeve g^4 mounted on a shaft g^5 , the end portions of which are secured in bearings g^6 secured to the opposite sides of the box or 30 casing c , and between the sleeve g^4 and the shaft g^5 are roller bearings g^7 , this construction, including the drum g^3 , the shaft g^5 , the bearings g^6 and the rollers g^7 being exactly the same as the corresponding parts at the 35 bottom of the box or casing, and including the sleeve f^4 , the roller bearings f^5 and the bearings f^2 of the shaft f , and being clearly shown in cross section in Fig. 9.

40 One end of the drum g^3 is provided with a small central grooved wheel g^8 on which is wound and to which is secured a cord h , preferably composed of wire, and one end of which is connected at h^2 with a lever h^4 pivoted to a support h^5 secured to the back 45 of the box or casing, and above the governor e^2 , and the other end of which is connected with the upper end of the rod e^8 at h^6 .

50 The support h^5 in the construction shown is yoke-shaped in form and connected therewith is a finger piece h^7 with which is connected a tension spring h^8 which is also connected with the lever h^4 , and which normally holds said lever in the position shown in Fig. 6.

55 The front of the signal box or casing c is cut out as shown at c^3 and mounted in said casing within the cutout portion c^3 is a transparent panel i mounted in suitable keepers i^2 and rearwardly of the transparent panel i is another translucent panel i^3 , the outer face of which is provided with numerals 3, 6, 9 and 12 arranged as shown in Figs. 3 and 6, and which are designed to indicate miles.

60 65 Pivots mounted between the transpar-

ent panel i and translucent panel i^3 and at the bottom thereof on a shaft j is an L-shaped frame j^2 in one part of which is mounted a translucent plate j^3 on which is marked the word "Stop," and the L-shaped frame j^2 where it is connected with the shaft j is provided with a projecting member j^4 which operates in connection with a bead or projection j^5 on the free edge portion of the shutter g^2 , and in the position of said shutter g^2 , as shown in Figs. 2, 6, 7 and 12, the projecting member j^4 is depressed by the bead or projection j^5 , and the L-shaped frame j^2 is thrown into the position shown in full lines in said figures, and when said shutter g^2 is raised, as hereinafter described, the L-shaped frame will drop into the position shown in dotted lines in Fig. 12 by its own weight, and this position of said frame is also shown in Fig. 3.

70 Supported centrally of the back of the box or casing c is an electric lamp bulb k , the wires k^2 of which extend out through the back of the box or casing, and connected with any suitable source of supply attached to the vehicle, and the operation of the device will be readily understood from the foregoing description when taken in connection with the accompanying drawing and the following statement.

75 In the position of the parts as shown in Figs. 2, 6, and 7, the vehicle is presumed to be at a standstill in which position the shutter g^2 is at the limit of its downward movement and in operative connection with the L-shaped plate j^2 and serves to hold the same in the position shown in said figure, and as shown in Fig. 2, all that will be seen on the casing c will be the black shutter at the bottom of which will appear the word "Stop" indicating that the vehicle is at a standstill.

80 In the movement of the vehicle, the rotation of the drive shaft b^3 will operate the governor shaft e through the flexible shaft d^4 and in proportion to the speed of the vehicle the shutter g^2 will rise by means of the operation of the governor e^2 . A sliding sleeve e^{10} of the governor operates in connection with the pin e^4 on the shaft e^3 and raises said shaft including the block head e^6 and rod e^8 which in turn operates the lever h^4 pulling the cord h downwardly and rotating the drum g^3 so as to raise the shutter g^2 and indicate the speed of the vehicle which, as shown in Figs. 3 and 6, is designated by numerals 3, 6, 9 and 12.

85 The movement of a vehicle on the crowded city streets is not a continuous movement at a predetermined speed but varies from three to six or eight miles an hour and sudden starts and stops are made, and by means of the apparatus herein described, it will be possible for the chauffeur of one vehicle to 90 determine whether a preceding vehicle is 95 100 105 110 115 120 125 130 135 140 145 150 155 increasing or decreasing in speed and thereby regulate the speed of his vehicle, and this also will enable chauffeurs to make greater headway due to the fact that no time will be lost to determine, whether or not, the preceding vehicle intends to decrease its speed, stop, or increase its speed.

In Figs. 4, 5 and 8, I have shown a modified form of means for indicating the movement 10 of the vehicle, in which form of construction the translucent panel j^3 may or may not be employed, and if employed the numerals 3, 6, 9 and 12 will not appear thereon, and the shutter g^2 instead of being provided with the 15 wire cords g is extended and passed around and secured to a drum m similar to the drum g^3 , and it will be understood that, in this construction, the grooved wheels f^6 are not employed. The shutter g^2 , in this form 20 of construction, is provided with two translucent strips n and n^2 being in the form of arrows n^3 and n^4 , and the arrow n^3 is directed downwardly while the arrow n^4 is directed upwardly.

25 The position shown in Fig. 4 corresponds to that shown in Fig. 2 in which the point of the arrow n^3 is directly above the L-shaped frame j^2 carrying the translucent plate j^3 in which position the head of the 30 arrow n^4 is directly back of said translucent plate j^3 , and the light from the electric lamp bulb k passes through the translucent strip n^2 , or the head portion of the arrow n^4 so as to illuminate the said plate j^3 . The position of the parts shown in Fig. 5 corresponds to that shown in Fig. 3 and indicates 35 that the vehicle is traveling at a high speed, this modification will operate to produce the same result as that shown in Figs. 2 and 3, 40 and other changes in and modifications of the various details of the construction herein shown and described, may be made, within the scope of the appended claims, without departing from the spirit of my invention or 45 sacrificing its advantages.

Having fully described my invention, what I claim as new and desire to secure by Letters Patent, is:—

1. In a device of the class described, a 50 suitable casing, a shutter mounted therein, means mounted in said casing and in operative connection with the driving mechanism

of a vehicle for operating said shutter, a stop indicating device mounted in said casing and means connected with said shutter 55 for operating said stop indicating device.

2. In a speed signal device for vehicles, a suitable casing the front of which is provided with an aperture, a transparent panel mounted in said aperture, a flexible shutter, 60 a drum mounted in the top of said casing and with which one end of said shutter is connected the other end of which is connected with a similar drum mounted adjacent to the bottom of said casing, a governor mounted in the bottom of said casing and in operative connection with said drum, means in operative connection with the driving mechanism of a vehicle for operating 65 said governor to operate said shutter, and 70 means whereby the operation of said shutter will operate a stop indicating device.

3. In a speed signal device for vehicles, a suitable casing the front of which is provided with an aperture, a transparent panel 75 mounted in said aperture, a translucent panel mounted rearwardly of said transparent panel and on which is arranged numerals indicating miles, a flexible shutter mounted in said casing and between said 80 transparent and translucent panels, means in operative connection with the driving mechanism of a vehicle for operating said shutter in the movement of said vehicle so as to indicate the speed thereof, and means 85 for indicating when said vehicle is at a standstill.

4. In a speed signal device for vehicles, a suitably supported flexible shutter, a governor in operative connection with said shutter, means in operative connection with the driving mechanism of a vehicle for operating 90 said governor, and a device operated by said shutter for indicating that a vehicle is 95 at a standstill.

In testimony that I claim the foregoing as my invention I have signed my name in presence of the subscribing witnesses this 1st day of November, 1915.

EDMUND SIMPSON.
